UNITED STATES PATENT OFFICE.

CICERO HINE, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

DESIGN FOR A GRILLE FOR TALKING-MACHINE CABINETS.

52,396.

Specification for Design.

Patented Sept. 10, 1918.

Application filed June 15, 1918. Serial No. 240,237. Term of patent 7 years.

To all whom it may concern:

Be it known that I, CICERO HINE, a citizen of the United States, residing at Chicago, in the county of Cook and State of Illinois, have invented a new, original, and ornamental Design for Grilles for Talking-Machine Cabinets, of which the following is a specification, reference being had to the accompanying drawing, showing a plan view of a grille embodying my invention.

I claim:

The ornamental design for a grille for talking machine cabinets as shown.

CICERO HINE.

Witness:

M. D. HENDRICKSON.
